[57] CLAIM

The ornamental design for a commode deodorizer unit, as shown and described.

DESCRIPTION

FIG. 1 is a perspective view taken from the top, front and right side of a commode deodorizer unit showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom view thereof.

The broken line representation of a ventilating tube in FIG. 1 is for purposes of illustration only and forms no part of the claimed design. The electric cord is broken away in FIGS. 3, 4, 6 and 7 for convenience of illustration.
